Atty

UNITED STATES PATENT OFFICE.

LORENZO L. WILLIAMS, OF MILFORD, CONNECTICUT.

MATCH-HOLDER ATTACHMENT FOR PACKAGES OF CIGARETTES.

Application filed February 12, 1925. Serial No. 8,668.

Fig. 1 A front view of a match-holder attachment for packages of cigarettes, constructed in accordance with my invention.

Fig. 2 A side view, partly in section, of 5 the same.

Fig. 3 A side view of the match-holder attachment, detached.

Fig. 4 A plan view, indicating a package of cigarettes with my improved match- 10 holder attachment connected therewith.

Fig. 5 A front view of the match-holder attachment, detached.

All figures of the drawings are on enlarged scale.

15 This invention relates to improvement in match-holder attachments for packages of cigarettes, the object of the invention being to provide a holder for packets of paper matches, which holder may be connected 20 with a package of cigarettes, and the invention consists in the construction as herein-after described and particularly recited in the claims.

In carrying out my invention, I employ a 25 strip of sheet-metal, celluloid, or other suitable material, doubled upon itself to form a back 10 and a front 11. Preferably, the back will be formed with a central, longitudinal slot forming fingers 12 and 13, the 30 width of the back corresponding substantially to the width of the package of cigarettes with which it is to be used. The side edges of the front 11 are turned inward to form flanges 14 and 15, and the lower end of the 35 front is slightly curved to form a lip 16. A packet 17 of paper matches is inserted between the flanges 14 and 15, and will be limited in its downward movement by the 40 lip 16. The fingers 12 and 13 will then be inserted into a package of cigarettes, between one of its outer faces 18 and the cigarettes contained therein. The advantage of forming the fingers 12 and 13 is that they 45 will enter on opposite sides of the revenue stamp which is usually applied over the end of the package of cigarettes, so that the stamp will not be broken by the introduction

of the match-holder. The fingers, however, are sufficiently rigid to reinforce one side of the package, and hence prevent the package 50 from being crushed in the pocket.

These holders can be struck up from sheet-material at very slight expense and fresh packets of matches can be inserted at pleasure, and removed when the cigarettes 55 are exhausted and applied to a fresh package.

I thus provide, in a very simple way, a means for attaching a packet of matches to a package of cigarettes. 60

I claim:

1. A match-holder attachment for packages of cigarettes, comprising a strip of sheet-material doubled to form a front and a back, the back adapted to be entered into 65 a package of cigarettes, and the front to overlie the outer face thereof, the side-edges of the front turned forward and inward to form flanges for the reception of the side-edges of a package of matches. 70

2. A match-holder attachment for packages of cigarettes, comprising a single strip of sheet-material doubled to form a front and a back, the back adapted to be entered into a package of cigarettes and the front 75 to overlie the outer face thereof, the side-edges of the front turned forward and inward to form flanges, and its lower-edge turned outward, forming a lip, whereby a package of matches may be readily detachably connected with a package of cigarettes. 80

3. A match-holder attachment for packages of cigarettes comprising a back and front formed from a single strip of sheet-material, the back formed with a longitudinal slot forming two fingers, the edges of the sides of the front turned inward, forming flanges for the reception of a packet of matches, the lower edge of the front formed with a lip to limit the downward movement 90 of the back.

In testimony whereof, I have signed this specification.

LORENZO L. WILLIAMS.
